(57) **CLAIM**

The ornamental design for a feeding tube set inlet component as shown and described.

DESCRIPTION

FIG. 1 is a front perspective view of a feeding tube set inlet component showing our new design;

FIG. 2 is a top plan view of the feeding tube set inlet component of FIG. 1;

FIG. 3 is a bottom plan view of the feeding tube set inlet component of FIG. 1;

FIG. 4 is a left side elevation view of the feeding tube set inlet component of FIG. 1;

FIG. 5 is a right side elevation view of the feeding tube set inlet component of FIG. 1;

FIG. 6 is a front end view of the feeding tube set inlet component of FIG. 1; and,

FIG. 7 is a rear end view of the feeding tube set inlet component of FIG. 1.

The broken lines shown in the figures depict portions of the feeding tube set inlet component that form no part of the claimed design.
